UNITED STATES PATENT OFFICE.

FRANK DEMMING MOSES, OF ZANESVILLE, OHIO.

APPARATUS FOR THE MANUFACTURE OF GAS.

SPECIFICATION forming part of Letters Patent No. 410,174, dated September 3, 1889.

Application filed May 15, 1889. Serial No. 310,812. (No model.)

To all whom it may concern:

Be it known that I, FRANK DEMMING MOSES, a citizen of the United States, residing at Zanesville, in the county of Muskingum and State of Ohio, have invented certain new and useful Improvements in Apparatus for the Manufacture of Gas; and I do hereby declare the following to be a full, clear, and exact description of the invention, such as will enable others skilled in the art to which it appertains to make and use the same.

The object of the invention is to provide a gas apparatus adapted to economically manufacture gas from soft or bituminous coal, and particularly from slack, culm, or breeze, with the aid of air and steam. To this end a special form and arrangement of what, for convenience, may be styled a "retort" or "retort chamber" has been devised in combination with a generator-chamber, the construction being such that gases from the gas-generator may be compelled to pass through the body of coal in the retort.

Heretofore vertical retort-chambers have been located above a fuel or steam decomposing chamber or generator; but such arrangement is to some extent defective in operation, for the reason that the charge of soft coal when partially fused and expanded by heat becomes packed and caked in the retort-chamber, requiring considerable mechanical force to break it up so that it can be forced down into the generator; and, further, the gases ascending through this mass of caked coal from the generator form for themselves irregular and fortuitous paths inconsistent with uniform and satisfactory results. Horizontal retorts have also been employed in gas-making furnaces in combination with generating-chambers. These afford more room for the expansion of the hot and semi-fused mass of coal; but they do not provide for the passage of gases through the coal, and they require an unnecessary amount of labor to break up the caked coal and force it into the generator.

My invention consists in a construction and arrangement of a fuel magazine or receptacle which may be called a "coking-chamber," that permits its contents to freely expand, and which also provides for passing hot gases from the generator transversely through the

coal in said chamber, and also provides for an easy and convenient transfer of the coal to the generator, the packing of the coking-coal in the coking-chamber being avoided by its freedom to expand upwardly and by the dividing effect of numerous transverse gas-currents.

In the accompanying drawings, Figure 1 is a vertical section of the generator and coking-chamber, and Fig. 2 is a view looking toward the outer end of the chamber.

I indicates the generator, made of brick, inclosed by metal or constructed in any suitable manner and provided with a door 2 and grate 3, and having in the ash-pit an air-inlet 4, a steam-inlet 5, and a gas-outlet 6. In the upper part of the generator is a steam-inlet 7. The charging-hole 8 is sealed in any usual manner. Communicating with the generator is an extension 9, styled, for convenience, a "coking-chamber," into which fresh coal is charged through a door 10, that can be closed gas-tight when desired. This extension may be made about three feet wide by two and a half feet in depth, and the generator about four feet in diameter, and each about ten feet in length, though these dimensions may be varied. The coking-chamber is provided, preferably below its central plane, with a perforated diaphragm 11, dividing its interior into a coal-chamber 12 and a combustion-chamber 13. The latter communicates with the generator by means of an annular flue 14, having openings 15 into the same.

16 indicates an air-inlet; 17, passages through the diaphragm; 18, a gas-outlet connecting through a water-seal with a scrubber and holder; 19, an outlet for waste or producer gas, which may be made to communicate with a gas-holder, and which is provided with a cover that can be made gas-tight when necessary.

20 indicates a modification of the retort in respect to the gas-outlet, and 21 a damper which may be used in connection therewith.

22 is a damper or cut-off which serves to prevent gases from the generator passing directly into the retort and compel them to pass into the annular flue, and thence into the combustion-chamber 13. This damper also serves to prevent the fresh coal from sliding or rolling down into the generator, particularly when

the retort is much inclined. The inclination illustrated of about one foot in three is a very suitable one.

The construction described is in operation 5 not inconsistent with the use of regenerators, which might conveniently be arranged to support the retort, though their use is not essential to my improvement, and the retort can be supported upon masonry of suitable character.

The operation of the apparatus above described is as follows: The generator is at first charged with coke or anthracite coal, which being ignited is raised to incandescence by 15 an air-blast introduced beneath the grate. The products of combustion enter the annular flue 14, and pass thence into the combustion-chamber 13, where they may be more completely burned by admission of air through 20 inlet 16. The hot gases pass through the perforated diaphragm and out of the exit 19. Fresh coal may be charged into the retort either before or after the above-described step. If charged previously, then the products of combustion which pass through 25 17 and 30 through the coal are partly decomposed, and the carbonic acid is converted into carbonic oxide and somewhat enriched by the coal gases, particularly if the air-supply in chamber 13 does not exceed the amount required to convert the producer-gas into carbonic acid and vapor of water. When the coke in the generator has been rendered incandescent, the air-supply 35 at 4 is cut off, and steam is admitted through 5 and passed up through the hot coal of the generator, which decomposes it, producing water-gas. This gas passes into the lower chamber of the retort and through the perforated diaphragm. The air-supply to the lower chamber having been cut off, the outlet 19 closed, and the gas-outlet 18 opened, the water-gas is passed therethrough to its holder. If the retort be charged with fresh 45 coal after the air-blast below the generator-grate is cut off and before the water-gas is passed through the retort, it serves to enrich the latter, air of course being excluded at every point. If the producer-gas is burned 50 in the retort and the carbonic acid thus produced not reconverted into carbonic oxide, as set forth above, the products are waste gases, and may be discharged into the open air or used to heat regenerators in the usual 55 way. Otherwise they may be conducted to boiler or other furnaces and burned while hot. Preferably the fresh coal is charged at a time when it will operate to enrich the water-gas rather than the producer-gas.

50 The use of the diaphragm to support the fresh coal and the passing of gases through the perforations 17 is an important feature. By this construction the gas is divided and made to pass through the coal in numerous 55 small currents, and this has the effect to thoroughly distill or expel the coal-gas, and

also to perforate or cut the coked coal in the line of each gas-passage 17. The contents of the retort when coked are therefore transversely honeycombed by the action of the 70 gases, and are very readily broken up when subsequently the damper or cut-off 22 is raised and the coke is pushed down the inclined diaphragm into the generator, the retort-door having been opened for the purpose. 75 The passages 17 are preferably constructed at the upper ends so that fine coal may not fall through them in any considerable quantity, and they are made wider at the bottom to facilitate the entrance of gases. 80

If desired, the damper 21 may be partially or wholly opened and a part of the producer-gas passed therethrough and out at 20, said outlet being connected with a gas-holder in any usual way. It is preferred, however, always to compel a considerable portion of the gases to pass transversely through the diaphragm and the coal resting thereon, and the gas may be taken out either at 18 or 20, waste or producer gas being taken out at 19. If desired, at suitable times steam can be admitted at 7 and passed down through the incandescent coke, and the water-gas thus produced can be taken out at 6, which may be found useful occasionally to avoid quenching the base of the fire by the too continuous introduction of steam at that point. 90

The use of the above-described apparatus, which may be varied as stated, is not inconsistent with the employment of two beds of 100 incandescent fuel through which steam may be passed in succession, nor with the use of oil as an enriching agent, nor with other well-known features of gas-making; but these are not of my invention, and are not essential to 105 the present improvement.

Having thus described my invention, what I desire to secure by Letters Patent is—

1. In a gas-making apparatus, the combination of the generator provided with air and steam pipes, the inclined coking-chamber connected to and communicating with the generator and provided with a perforated diaphragm, a conduit communicating with the generator-chamber and with a space 115 below the said diaphragm and adapted to conduct products of combustion from the generator to the said space, and a cut-off or damper to prevent direct communication from the generator to the upper part of the retort, 120 substantially as set forth.

2. In a gas-making apparatus, the combination of the generator provided with air and steam pipes, the inclined coking-chamber connected to and communicating with the generator and provided with a perforated diaphragm, a conduit communicating with the generator-chamber and with a space 125 below the said diaphragm and adapted to conduct products of combustion from the generator to the said space, a cut-off or damper to prevent direct communication from the 130

generator to the upper part of the retort, and an air-inlet to the retort, substantially as set forth.

3. In a gas-making apparatus, the combination of the generator provided with air and steam pipes, the inclined coking-chamber connected to and communicating with the generator and provided with a perforated diaphragm, a conduit communicating with the generator-chamber and with a space below the retort-diaphragm and adapted to conduct products of combustion from the generator to the said space, a cut-off or damper to prevent direct communication from the generator to the upper part of the retort, an air-inlet to the retort, a damper or cut-off in the diaphragm, substantially as set forth.

4. In a gas-making apparatus, the combination of the generator provided with air and steam pipes, the inclined coking-cham-

ber connected to and communicating with the generator and provided with a perforated diaphragm, a conduit communicating with the generator-chamber and with a space below the retort-diaphragm and adapted to 25 conduct products of combustion from the generator to the said space, a cut-off or damper to prevent direct communication from the generator to the upper part of the retort, an air-inlet to the retort, a damper or cut-off in 30 the diaphragm, and an outlet for gas from the retort located near the cut-off which excludes direct communication from the generator, substantially as set forth.

In testimony whereof I affix my signature in 35 presence of two witnesses.

FRANK DEMMING MOSES.
